UNITED STATES PATENT OFFICE.

ROBERT S. ORR, OF PITTSBURGH, PENNSYLVANIA, ASSIGNOR TO PITTSBURGH REINFORCING POLE COMPANY, OF PITTSBURGH, PENNSYLVANIA, A CORPORATION OF PENNSYLVANIA.

REINFORCING-POLE.

1,080,525.

Specification of Letters Patent.

Patented Dec. 2, 1913.

Application filed April 5, 1909. Serial No. 488,083.

To all whom it may concern:

Be it known that I, ROBERT S. ORR, of Pittsburgh, in the county of Allegheny and State of Pennsylvania, have invented a new 5 and useful Improvement in Reinforcing Poles, of which the following is a full, clear, and exact description, reference being had to the accompanying drawings, forming part of this specification, in which—

10 Figures 1 and 2 are vertical sectional views showing two different forms of my invention.

My invention relates to reinforcing worn or partly worn or decayed wooden poles by 15 the use of reinforced concrete and is designed to provide a system in which it is not essential to connect both ends of the reinforcing members to the pole, as shown in my United States Patent 892,880, dated July

20 7, 1908.

In the drawing, 2 represents the worn or rotted portion of the pole which usually extends slightly above and slightly below the ground level, as shown. In treating such 25 poles, I practically clean away the decayed or worn portions to expose sound wood, I then secure the upper ends of reinforcing bars 3 to the pole above the weakened portion. This may be done by driving spikes 30 4 through suitable holes in the bars, which in this case are shown as rolled angle bars. A series of these bars may be arranged around the pole with their upper ends spiked to it, as shown, their lower ends de- 35 pending within a dug out portion of the ground surrounding the pole, and extending below the weakened portion. In order to more firmly connect the concrete to the pole, I may also drive in spikes or connecting 40 members 5 below the weakened portion. After these reinforcing parts are in place, they are then embedded in a body of plastic material, such as concrete or cement 6, which may be molded in any desirable man- 45 ner, and preferably extends above and below the reinforcing members so as to inclose them, though this is not essential.

In Fig. 2, I show a form similar to that of Fig. 1, except that small channels or I-beams 3^b are used in place of the angle bars 50 of Figs. 1 and 2. In this case also, I show the reinforcing members as extending above the concrete.

It will be observed that in all the forms of my invention illustrated the flanges of 65 the bars not only increase the compression strength of the bars themselves, but that they also engage the concrete in a manner to oppose the maximum resistance of the latter to compression or buckling strains in 60 the members. In this manner the concrete not only acts as a filling and anchoring body, but it is made both directly and through the bars to act itself as an efficient compression member. 65

The invention may be applied to new poles, the form and size of the reinforcing members may be varied, and they may be attached to the pole in different ways, without departing from my invention. 70

I claim:

The combination with a pole having a weakened base portion of reduced cross-section, of a reinforce therefor, said reinforce comprising a body of concrete surrounding 75 the pole from a point below its weakened portion to a point above the same, and anchored to the pole, and metallic bracing members secured to the pole at their upper ends and extending obliquely downwardly 80 and outwardly within the concrete body to points below said weakened portion, said bracing members having laterally extended flanges which increase their compression strength, and which also engage the concrete to oppose the resistance of the latter to compression or buckling strains in the members; substantially as described. 85

In testimony whereof, I have hereunto set my hand.

ROBERT S. ORR.
